(57) **CLAIM**

The ornamental design for a roll-up window cover with hook and loop fasteners, as shown and described.

DESCRIPTION

FIG. 1 shows a front and side perspective view of a roll-up window cover with hook and loop fasteners.

FIG. 2 shows a front elevation view thereof.

FIG. 3 shows a rear elevation view thereof.

FIG. 4 shows a right side view thereof.

FIG. 5 shows a left side view thereof.

FIG. 6 shows a top plan view thereof.

FIG. 7 shows a bottom plan view thereof; and,

FIG. 8 shows a top and side perspective view of the window cover in a rolled-up configuration. The broken lines in the drawings represent stitching, which form a part of the claim.

1 Claim, 5 Drawing Sheets
